UNITED STATES PATENT OFFICE.

ANDREW P. NORDEEN, OF MISSOURI VALLEY, IOWA.

PROTECTOR FOR DRAFT-TIMBERS.

No. 899,554.

Specification of Letters Patent.

Patented Sept. 29, 1908.

Application filed January 8, 1908. Serial No. 409,875.

To all whom it may concern:

Be it known that I, ANDREW P. NORDEEN, a subject of the King of Sweden, residing at Missouri Valley, in the county of Harrison 5 and State of Iowa, have invented certain new and useful Improvements in a Protector for Draft-Timbers, of which the following is a specification.

This invention relates to certain new and 10 useful improvements in a protector for the ends of draft timbers, such as are used on cars of various kinds, and it consists in certain peculiarities of the construction, novel arrangement, and operation of the parts 15 thereof, as will be hereinafter more fully set forth and specifically claimed.

The object of the invention is to provide a 20 protector for draft timbers which shall be simple and inexpensive in construction, strong, durable and efficient in operation, and so made that it may be readily secured 25 in place and in such a manner as to prevent the end of the timber on which it is secured becoming battered or broken by reason of contacting with other timbers or parts of cars.

In order to enable others skilled in the art 30 to which my invention pertains, to make and use the same, I will now proceed to describe it, referring to the accompanying drawing, in which—

Figure 1 is a perspective view of a portion 35 of two draft timbers of a car, showing their front ends equipped with protectors therefor embodying my invention, and illustrating by dotted lines the position the draw-head will occupy; Fig. 2 is a top plan view of a portion 40 of one of the draft timbers, showing the protector secured thereon; Fig. 3 is a longitudinal sectional view taken on line 3—3 of Fig. 1 looking in the direction indicated by the arrows; and Fig. 4 is a detached bottom perspective view of the protector.

Like numerals of reference, refer to corresponding parts throughout the different 45 views of the drawing.

As my invention relates simply to means 50 for protecting the ends of the draft timbers of cars, I have not deemed it necessary to elaborate 55 illustrate the car construction, but have only shown in Fig. 1 of the drawing two draft timbers 5—5 which are located in parallelism with one another in the usual manner on the car-frame, and have at their

front portions a transverse sill or beam 6, 55 which is commonly known as the dead wood, and which is secured to the draft timbers 5—5 by means of bolts 7 extended through suitable openings in the piece 6 and timbers 5, as well as in the top portion of the protector. 60

Fitted on the front end of each of the draft timbers 5 is a protector 8 therefor, which may be made of any suitable size and material, but preferably of malleable cast 65 iron, and substantially of the form shown in the drawing. That is to say, the protector is formed box-like in shape and has a rectangular cavity 9 in which the end of the draft timber is fitted.

As shown in Fig. 4 of the drawing, in 70 which view I have illustrated the protector in an inverted position, it will be understood that the bottom and rear end of the protector 8 is left open while its front end is formed with a vertically extending and rounded enlargement 10 on its outer surface, while the interior of the cavity 9 at said corner is formed with two obtuse angles 11, thus furnishing a thickened portion 12, which when 75 the protectors are in position on the draft timbers, will be located at the adjacent corners of said timbers, which corners may be cut away as shown by dotted lines in Fig. 2 to correspond in shape with the angles 11 of 80 85 the cavity of the protector. The rear portion of each of the side walls of the protector is provided with an opening 13 through which a bolt 14 is passed to secure the protector in place on the timber. The top of the protector is also provided with openings 15 for the reception of the bolts 7 which are used for securing the dead timber in position.

From the foregoing and by reference to the drawing it will be seen and clearly understood that by employing a device embodying 95 my invention a very simple, inexpensive, convenient and durable protector for draft timbers is furnished and one that can be readily applied to the timbers or removed 100 therefrom, when desired.

Having thus fully described my invention, what I claim as new, and desire to secure by Letters-Patent, is—

1. As an improved article of manufacture, 105 a protector for draft timbers consisting of a box-like body having its rear end and bottom open and provided at its front end with

a vertically disposed enlargement located at one of the corners of the body.

2. As an improved article of manufacture, a protector for draft timbers consisting of a box-like body having its rear end and bottom open and provided at its front end with a vertically disposed enlargement located at

one of the corners of the body, the cavity of the body being formed with obtuse angles near the said enlargement.

ANDREW P. NORDEEN.
